UNITED STATES PATENT OFFICE.

ULRICH B. NEWMAN, OF GREENFIELD, OHIO.

STOVE-HOOD.

SPECIFICATION forming part of Letters Patent No. 379,323, dated March 13, 1888.

Application filed April 19, 1887. Serial No. 235,400. (No model.)

To all whom it may concern:

Be it known that I, ULRICH B. NEWMAN, a citizen of the United States, residing at Greenfield, in the county of Highland and State of Ohio, have invented a new and useful Improvement in Stove-Hoods, of which the following is a specification.

My invention relates to a stove-hood adapted to be suspended over a cooking-stove to receive the smoke, steam, and odor from the cooking and convey it to the chimney to prevent the same from circulating through the house, it being in some cases very unpleasant and annoying. I attain this object in the construction and arrangement of parts, as fully described hereinafter, specifically pointed out in the claim, and illustrated in the accompanying drawings, in which—

Figure 1 is a perspective view of a cooking-stove having my hood suspended properly thereover in the operative position. Fig. 2 is a detail section (vertical) through the hood. Fig. 3 is a detail view of the support.

Referring to the drawings by letter, A designates the funnel-shaped hood, the base of which may be either round or elliptical, and B is a small pipe having a screw or other detachable coupling to the upper end of the hood, the said pipe being adapted to connect with the smoke-pipe of the stove or directly with the chimney.

C represents a support for the said hood, comprising the parallel laterally-extending arms c' c'' and the collar c on the ends thereof, having ears c^2 c^3 , provided with aligned perforations to receive a set-screw, c^3 . The said collar is adapted to be placed around the stove-pipe or a similar vertical support, and the ears on the said collar are drawn together by means of the set screw to clasp the said pipe tightly and support the hood. It will be seen that the collar will fit pipes of different sizes, and may be adjusted vertically at will.

Around the inner lower edge of the hood is formed a groove or gutter, D, adapted to collect all the moisture which condenses on the inner sides of the hood, and G is a small tube leading from the lowest point of the said groove to convey the said condensed moisture to any convenient or desired receptacle.

The hood is suspended, in the manner described, over the portion of the stove on which the cooking is done, and the fumes, steam, &c.,

rising therefrom will be received in the hood and conveyed to the flue, where it will escape, 55 the draft caused through the said hood by the smoke-flue also aiding in drawing all of the said fumes into the hood and up the chimney.

The steam passing through the hood is in part, at least, condensed upon the sides of the 60 same, and, gathering in drops, passes down the said sides and into the groove around the lower edge thereof, from which it is conveyed, as described, by the tube G to a suitable receptacle, the object, as is obvious, being to 65 prevent dripping on the stove, which would interfere with the cooking.

The conductor or hood, as described, will be found of great utility and very effective in operation, conveying all smoke, fumes, &c., 70 from the room, thus preventing the unpleasant odor of cooking from permeating the house, as it invariably does when a device of a similar kind is not used; also, the device is very simple, and may be cheaply manufactured, 75 being preferably made of sheet metal.

The screw-connection between the upper end of the hood and the pipe to carry off the odor is novel, and will be found very convenient in attaching and detaching the said hood, 80 thus enabling the same to be readily taken down when desired.

I do not wish to be understood as limiting myself to the precise construction and arrangement of parts as herein described, as I 85 may alter the same somewhat without departing from the spirit of the invention.

Having now described the construction, operation, and advantages of my invention, I claim—

In a stove-hood, the combination of the hood A, the pipe B, leading therefrom, the support C, to be attached to the stove-pipe, the groove D around the inner lower edge of the hood to collect the moisture condensed on the 95 inner walls of the hood, and the tube G, communicating at the upper end with the said groove to convey away the accumulated moisture, substantially as specified.

In testimony that I claim the foregoing as 100 my own I have hereto affixed my signature in presence of two witnesses.

ULRICH B. NEWMAN.
